UNITED STATES PATENT OFFICE.

JOHN R. BARRETT, OF CHICAGO, ILLINOIS.

TEMPORARY BINDER.

SPECIFICATION forming part of Letters Patent No. 751,710, dated February 9, 1904.

Original application filed January 17, 1899, Serial No. 702,483. Divided and this application filed May 24, 1902. Serial No. 108,851.
(No model.)*To all whom it may concern:*

Be it known that I, JOHN R. BARRETT, a citizen of the United States, residing at Chicago, in the county of Cook and State of Illinois, 5 have invented certain new and useful Improvements in Temporary Binders, of which the following is a specification, reference being had to the accompanying drawings.

My invention relates to temporary binders 10 of the well-known Emerson type, and has for its object to provide certain improvements in such binders.

It consists in an improved construction by 15 which the binding-cord is carried and prevented from slipping.

What I regard as new will be set forth in the claims.

In the accompanying drawings, Figure 1 is a perspective view of a binder, illustrating my 20 improvements. Fig. 2 is a partial cross-section on line 2 2 of Fig. 1. Fig. 3 is a partial longitudinal section of one of the side strips on line 3 3 of Fig. 1. Fig. 4 is a partial cross-section on a line corresponding to line 2 2 of Fig. 1, illustrating a modification. Fig. 5 is 25 a perspective view further illustrating the construction shown in Fig. 4. Fig. 6 is a view similar to Figs. 2 and 4, showing another modification; and Fig. 7 is a perspective view 30 further illustrating the construction shown in Fig. 6.

Referring to the drawings, 8 9 indicate the covers, which are connected by the usual flexible center piece 10, as shown in Figs. 1 and 2. 35 The covers 8 9 are provided, respectively, with side strips 11 12 in the usual way, said side strips being arranged to carry the cord and the cleats to which the ends of the cord are secured. As illustrated in Figs. 1 and 2, 40 one of the side strips, as 11, is provided with perforations 13 14 near its ends and with two perforations 15 16, respectively, arranged in juxtaposition near the center thereof. (See Figs. 1 and 3.) The perforations 15 16 are 45 for the purpose of securing the intermediate portion of the binding-cord 17 at the longitudinal center of the binder to prevent endwise movement thereof. This is accomplished by passing the cord 17 twice through said per-

forations, as illustrated in Fig. 3, forming a 50 loop which incloses said perforations. As clearly shown in Fig. 3, the cord is passed through perforation 15, thence back through perforation 16, thence again through perforation 15, and back through perforation 16, so 55 that it is looped around that part of the strip 11 which lies between said perforations, thereby effectually preventing longitudinal movement thereof under any strain to which it would normally be subjected in a binder. It 60 will be observed that one of the ends of the cord extends from the perforation 15 through perforation 13 near one end of the strip 11, the opposite end of the cord passing through the perforation 14 at the opposite end of said 65 strip.

The strip 12 is provided with cleats 18 19, arranged, respectively, opposite the perforations 13 14 of the strip 11, as shown in Fig. 1, and, as best shown in Fig. 2, each of said cleats 70 is provided with a central passage 20, through which the cord 17 is adapted to pass, as shown in Fig. 2. The arrangement is such that the ends of the cord after being passed downward through perforations 13 14 in the strip 12 may 75 be passed upward through the passages 20 in the cleats 18 19 of the strip 12 to the upper side of said strip, on which said cleats are secured, and may then be belayed upon said cleats, as illustrated in Fig. 1. As is well understood, the papers, magazines, or other documents are secured between the opposite surfaces of the strips 11 12, and the cord 17 passes through the inner margins of the papers and when drawn taut and secured to the cleats 80 serves to bind the strips 11 12 tightly against the papers in the binder. As shown in Fig. 2, the strips 11 12 are flexibly secured in position, so that they may adjust themselves to the surface of the contents of the binder. 90 This arrangement is best secured by inclosing the strips 11 12 in a canvas covering 21, the edges of which are secured to the covers 8 9. The binding-strips will thus move independently of the covers, and the binder may be 95 easily and quickly filled or emptied.

In order to accommodate the strips 11 12 with the cord and cleats, so that when the cov-

ers are closed they may lie flatly upon the contents of the binder, I provide recesses adapted to receive such strips when the covers are closed. In Figs. 1 and 2 I have illustrated 5 one form of construction for this purpose. In the construction shown in said figures the recesses are provided by reducing the thickness of the covers 8 9 along their inner margins, the reduction in thickness being on the 10 inside surface, so that depressions 22 23, respectively, are provided which extend from top to bottom of the covers, as shown in Fig. 1. I prefer to make the covers of two thicknesses of cardboard *a b*, as shown in Fig. 2, 15 the board *a* being of less width than the board *b*, so that by arranging the two boards with their outer margins coincident the depressions 22 23 are provided at the inner margins. The boards *a b* are secured together by suitable 20 binding material.

Where it is not deemed necessary to provide recesses to accommodate the strips 11 12 throughout their length, but only to provide recesses opposite the cleats, I may cut out suitable recesses in the cover, as shown in Figs. 4, 25 5, and 6. Where the covers are of single thickness and it is necessary to cut entirely through or almost entirely through the covers to provide recesses of sufficient depth, I 30 provide plates 24 of suitable shape to fit into said recesses and provided with flanges *c d e*, adapted to rest upon the inner surface of the cover and be secured thereto, as shown in Fig. 5. While by this construction I provide recesses at the points where they are most needed, I prefer to provide the depressions or 35 recesses 23, extending from top to bottom of the covers, as by that means not only are the cleats accommodated, but also the strips to which 40 they are attached. In Fig. 4 I have shown the recesses in both covers, because it is sometimes desirable to provide cleats on both strips 11 12, as shown in said figure; but it is not essential to provide the recesses in both 45 covers. Where covers of double thickness are used, it is not necessary to employ the metallic plates 24, as recesses 25 may then be provided by simply cutting into the inner margins of the covers to a suitable depth, as 50 shown in Figs. 6 and 7. When this construction is employed, the recesses 25 are lined with the material 21, which incloses the strips 11 12, as shown in Fig. 6.

A binder is thus provided in which the bind-

ing-strips will move out of the recesses when 55 the binder is opened and lie flat in said recesses when the binder is closed, and the covers will always lie flat regardless of whether or not the binder is filled.

This application is filed as a division of my 60 pending application, Serial No. 702,483, filed January 17, 1899.

That which I claim as my invention, and desire to secure by Letters Patent, is—

1. In a binder, the combination with covers, of binding-strips, 11 12, one of said strips having perforations 13 14 and intermediate perforations 15 16, and a binding-cord, the intermediate portion of said cord forming a loop around that portion of the strip lying 70 between said perforations 15 16, the ends of the cord passing through the perforations 13 14, substantially as described.

2. In a binder, the combination with covers, of binding-strips, 11 12, one of said strips 75 having perforations 13 14 and intermediate perforations 15 16, and a binding-cord, the intermediate portion of said cord forming a loop around that portion of the strip lying between said perforations 15 16, the ends of 80 the cord passing through the perforations 13 14, the other strip having means for securing the ends of the cord, substantially as described.

3. In a binder, the combination with covers, of binding-strips, 11 12, one of said strips having perforations 13 14 and intermediate perforations 15 16, and a binding-cord, the intermediate portion of said cord forming a loop around that portion of the strip lying 90 between said perforations 15 16, the ends of the cord passing through the perforations 13 14, the other strip having cleats 18 19, said cleats having central passages 20, substantially as described.

4. In a binder, the combination with covers, of binding-strips, 11 12, one of said strips having perforations 15 16 near the center thereof, a binding-cord, the intermediate portion of said cord forming a loop around that 100 portion of the strip lying between said perforations, and means near the ends of said strip for securing the ends of the cord, substantially as described.

JOHN R. BARRETT.
